US00D935472S

(12) **United States Design Patent** (10) **Patent No.:** **US D935,472 S**
Bieter et al. (45) **Date of Patent:** ** *Nov. 9, 2021

(54) **DISPLAY SCREEN OR PORTION THEREOF WITH GRAPHICAL USER INTERFACE**

(71) Applicant: **Thomson Reuters Enterprise Centre GmbH**, Zug (CH)

(72) Inventors: **Nicholas Bieter**, Saint Paul, MN (US); **Brittany Shada**, Farmington, MN (US); **Chris Moellering**, Farmington, MN (US); **Jeff Arvidson**, Eagan, MN (US); **Doug Wozniak**, Eagan, MN (US)

(73) Assignee: **THOMSON REUTERS ENTERPRISE CENTRE GMBH**, Zug (CH)

(*) Notice: This patent is subject to a terminal disclaimer.

(**) Term: **15 Years**

(21) Appl. No.: **29/656,218**

(22) Filed: **Jul. 11, 2018**

(51) LOC (13) Cl. **14-04**

(52) U.S. Cl.

USPC **D14/485**

(58) **Field of Classification Search**

USPC D14/485-495

CPC G06F 3/048; G06F 3/0481

See application file for complete search history.

Primary Examiner — Rachel A. Voorhies

(74) Attorney, Agent, or Firm — Thomson Reuters

(57) **CLAIM**

The ornamental design for a display screen or portion thereof with graphical user interface, as shown and described.

DESCRIPTION

The sole FIGURE is front view of a display screen or portion thereof with graphical user interface showing our new design.

The broken line showing of the display screen or portion thereof and the remainder of the graphical user interface is for environmental purposes only and forms no part of the claimed design.

1 Claim, 1 Drawing Sheet
